UNITED STATES PATENT OFFICE.

WILLIAM EVANS, OF PHILADELPHIA, PENNSYLVANIA, ASSIGNOR TO JOHN EVANS' SONS INC., OF PHILADELPHIA, PENNSYLVANIA, A CORPORATION OF PENNSYLVANIA.

LEAF-SPRING-EYELET-FORMING MACHINE.

Application filed December 18, 1922. Serial No. 607,664.

To all whom it may concern:

Be it known that I, WILLIAM EVANS, a citizen of the United States, residing at Philadelphia, in the county of Philadelphia and State of Pennsylvania, have invented new and useful Improvements in Leaf-Spring-Eyelet-Forming Machines, of which the following is a specification.

This invention relates to a leaf spring eyelet forming machine and the principal object is to produce a simple and efficient means for forming eyelets in the ends of leaf springs.

Another object is to provide improved means for gripping and forming the spring.

Another object is to produce a device of this nature which shall consist of few parts, cheap to manufacture, easy to assemble and operate, and highly efficient for the purpose for which it is designed.

Another object is to provide adjustable means for taking care of different sizes and thicknesses of springs.

With these and other objects in view as will be more apparent hereinafter, the invention consists in certain novel construction and combination and arrangement of parts, the essential features of which are hereinafter fully described, are particularly pointed out in the appended claims, and are illustrated in the accompanying drawings, in which:—

Figure 1 is a top plan view of my improved machine.

Fig. 2 is a vertical sectional view taken on line 2—2 of Fig. 1.

Fig. 3 is a front elevation of the machine.

Fig. 4 is a detail of one portion of the lever construction.

Fig. 5 is an enlarged detail of the spindle members.

Like characters of reference refer to like parts in all the views.

The present invention contemplates the providing of a mechanical means for gripping the ends of leaf springs such as are used for automobiles, and of turning in the end of each spring operated on, an eyelet or ring to receive the shackle bolt as will be readily understood by those skilled in the automobile art.

Referring to the accompanying drawing, 10 represents legs or supports which are shown as of angle iron although any suitable means may be used for this purpose.

Supported by the legs 10 is a table or superstructure 11 having a key-way 12 cut in its upper face.

A pair of bearing brackets 13 are formed with keys 14 in their bases which keys are seated in the ways 12 so as to hold the brackets 13 in their required position, said brackets being secured to the table 11 by bolts 15 or any other suitable and desirable means. The brackets 13 are formed at their upper ends into bearings 16 which receive and rotatably support cylindrical trunnion elements 17 of an operating frame 18. The elements 17 are drilled through and support stub-shafts 19 and 20.

The frame 18 is a U-shaped device having legs 21 and 22 which carry at their front ends the trunnions 17, and which are connected at their rear ends by a web portion having an aperture 23. Extending downwardly from the legs 21 and 22, are ears 24 which support between them a short shaft 25 held in place by a cotter-pin 26. Supported upon the shaft 25 between the ears 24 is a sleeve 27 carrying an upwardly extending web 28. Secured to the upper end of the web 28 is a gripping member or jaw 29 which is formed with an arcuate front face having a plurality of transverse teeth 30. Secured to or formed integrally with the jaw 29 is an upstanding member or bar 31, the upper end of which is embraced by a pair of links 32, bar 31 and links 32 being connected by a pin 33 having a finger-piece 34 whereby it may be easily inserted and withdrawn. Links 32 are arranged parallel with each other and are connected by a bolt 35 with a hand lever or operating member 36, the lower end of which is pivotally connected at 37 between the cheeks 38 of a clevis member 38 rigidly secured to the rear portion of the U-frame 18. A bar or short rod 39 is secured in the clevis member 38 so that the U-frame may be lifted up by hand in withdrawing or replacing parts. The purpose of the aperture 23 heretofore mentioned is so that a bar may be inserted therein to permit two persons to operate on the press when very heavy work is being operated on.

The inner ends of the stub shafts 19 and 20 heretofore mentioned project beyond the faces of the legs 21 and 22 and are drilled radially so as to provide apertures or sockets 30 for the reception of the turned down 110

ends 41 of a mandrel 42, the diameter of the body portion of the mandrel being the same as the inside diameter of the required spring loop or eyelet. The shaft 20 is held 5 in any desired position to which it is moved, by means of a set-screw 43; and the shaft 19 is provided at its outer end with a circumferential groove 44 into which a pin 45 projects. The pin 45 is carried by the upper 10 of two parallel links or levers 46 which extend substantially from the front to the rear of the machine at the right hand side thereof and which are held in spaced relation by bolts 47 and sleeves or washers 48. Mounted 15 between the front pair of washers 48 is a hand lever 49 which may be held in rigid extended relation by a pin 50. Upon withdrawing the pin 50, the hand lever 49 may be folded rearwardly. Between the rear 20 pair of sleeves 48 is secured a bar 51 which is fastened at 52 to the top of a column or post 53 rising from the base 11.

It will be seen that by means of the mechanism just described the stub-shaft 19 25 may be moved inwardly and outwardly at will, and yet will be rotatable in the bearing. Secured by a hinge 54 to the front of the table 11 is a work receiving end guiding support 55 having upturned ears or edges 30 56 and provided with set-screws 57. Bars 58 are utilized to fill out from the left hand guide 56 so as to accommodate the device to various sizes of springs. The various 35 thickness of the spring operated upon will determine the distance desirable between the inner end of the member 55 and the mandrel, and in order to adjust this, an adjusting screw 59 is provided to move the device 55 to the desired position.

40 The operation of the device may be described as follows:

The metal which is to be worked upon is shown at A and is a strip of metal which has been chamfered at its end and bent slightly 45 upwardly before being placed in the machine. The metal is also preferably previously heated and is then thrust into the machine along the guiding plate 55 between the set-screw 57 and the plates 58 50 until the rear end of the metal is in rear of the mandrel 42 and forward from the serrated or toothed jaw 29. The operator then draws forward on lever 36 which by means of links 32 forces the jaw 29 against 55 the end portion of the strip of metal so as to bring it into initial contact with the

mandrel, the teeth biting into the heated metal so as to prevent slipping of the jaw thereon in the succeeding operation. The lever 36 is then drawn further forward with 60 the result that the entire frame 18 is moved on the trunnions 17 in the bearings 16 so that the metal is wound or drawn around the mandrel, thereby forming an eyelet in the end of the strip. It is of course understood 65 that various sizes of mandrels may be used and that different forms of jaws 29 may be placed on the shaft 25, the construction permitting of the ready manipulation of parts for this purpose. It will also be understood that as soon as the eyelet is bent, the handle 49 may be thrown to the right thereby releasing the mandrel so that the eyelet and spring may be readily withdrawn.

75 While I have described what I deem to be the most desirable embodiment of my invention, I do not limit myself to the specific details of construction or material, nor to anything less than the whole of my invention as defined in the appended claims.

What I claim is:—

1. In a device of the class described, the combination of a supporting device, an operating frame rotatably supported thereby, an adjustable work support and guide, co-operative with said frame, a mandrel supported concentric with the axis of said frame, a jaw rotatably mounted on said frame and adapted to grip material interposed between said jaw and said mandrel, and a handle pivotally mounted on said frame and connected to said jaw for first operating said jaw and thereafter operating said frame.

2. In a leaf spring eyelet forming machine, a main frame-work, bearings supported thereby, a U-shaped frame rotatably supported in said bearings, a mandrel mounted concentric with the axis of said frame, an adjustable work support and guide co-operating with said frame, a jaw rotatably mounted on said frame and adapted to grip material interposed between the jaw and mandrel, and a handle pivotally mounted on said frame and connected to the jaw for first operating the jaw and thereafter operating said frame.

100 In testimony whereof I affix my signature.

105 WILLIAM EVANS.
